Term of patent 14 years

(Cl. D55—1)

FIG.1

FIG.2

FIG.3

FIG.4

FIG.5

FIGURE 1 is a perspective view of a high speed mixing rotor showing my design,

FIGURE 2 is a perspective view thereof with the rotor inverted from its position in FIGURE 1,

FIGURE 3 is a side elevational view of the rotor,

FIGURE 4 is a top plan view of the rotor as shown in FIGURE 3, and

FIGURE 5 is a bottom plan view of the rotor as shown in FIGURE 3.

This application is a continuation-in-part of my prior copending application Serial Number D. 82,379, filed Oct. 29, 1964, for High Speed Mixing Rotor, and now abandoned.

I claim:

The ornamental design for a high speed mixing rotor, as shown.
